(No Model.)

C. D. SPRAGUE.

GRAIN METER.

No. 471,034.

Patented Mar. 15, 1892.

UNITED STATES PATENT OFFICE.

CHARLES D. SPRAGUE, OF BLAIRSTOWN, MISSOURI.

GRAIN-METER.

SPECIFICATION forming part of Letters Patent No. 471,034, dated March 15, 1892.

Application filed April 8, 1891. Serial No. 388,125. (No model.)

To all whom it may concern:

Be it known that I, CHARLES D. SPRAGUE, of Blairstown, in the county of Henry and State of Missouri, have invented a certain new and useful Improvement in Grain-Meters, of which the following is a full, clear, and exact description, reference being had to the accompanying drawings, forming part of this specification.

10 My invention relates to an improved device for automatically measuring grain, and it is intended more particularly for use in connection with thrashing-machines to measure the grain as it comes from the machine.

15 My invention consists in features of novelty hereinafter fully described, and pointed out in the claims.

Figure I is a side elevation of my improved register. Fig. II is a front elevation. Fig. 20 III is a side elevation showing the other side of the device to that shown in Fig. I and showing the measuring-boxes in the act of turning.

Referring to the drawings, 1 represents a suitable frame, which may be of any desired form or shape, and in which are pivoted at 2 the grain-receiving boxes 3 4, the bottoms of which are indicated by the dotted lines A. The boxes are connected by a web or connection 5, so as to revolve together, and the back 30 4^a of one of the boxes is in line with the back 3^a of the other box, as shown by the dotted lines in Fig. III, and the pivot 2 is on a line with these backs, so that the boxes 3 and 4 are on opposite sides of the pivot. The normal position of the boxes is that shown in Fig. 35 I, in which position they are held by a projection 6 on the lower outer corner of the upper box bearing against the outer inturned end 7 of a lever 8, pivoted to the frame at 9 and provided with an adjustable counterbalance-weight 10 on the opposite side of the pivot 9 from the end 7 of the lever. Each box has a projection 6 for coming against the end 7 of the lever.

45 The grain is deposited into the boxes through means of a suitable chute 11, and the box receiving the grain, being forward of the pivot 2, has a tendency to revolve in the direction of the arrow, Fig. I, and when the necessary amount of grain has been deposited in it, it will revolve by depressing the

outer end of the lever 8 and causing the projection 6 to pass the end 7 of the lever. The counterbalance-weight 10 is shifted to the proper position, so that when just the proper 55 amount of grain has been received by the upper box its weight will cause the inner end of the lever to be depressed and the projection 6 to pass the end 7 of the lever. As soon as the projection passes the end 7 of the lever 60 the boxes revolve freely around, bringing the lower one uppermost to receive the grain and causing the contents of the box which was uppermost to be deposited into a suitable receptacle.

65 As soon as the boxes commence to turn the discharge of the grain from the chute 11 is automatically closed through means of a lever 12, pivoted to the frame 1 at 13 and having a projection 14 on its lower end, which 70 bears against a cam 15, secured to the spindle of the boxes, by which the boxes are pivotally supported. The upper end of the lever is connected by a link 16 to an end piece 17 of the chute 11, which is pivoted at 18 to the 75 chute. When the boxes are in their normal position, the projection 14 fits in recesses 19 in the periphery of the cam, and as soon as the boxes start to turn, carrying with them the cam, the lever 12 is moved to the position 80 shown in dotted lines, Fig. I, or to the position shown in full lines, Fig. III, bringing the hinged end 17 up against the mouth of the chute and shutting off the deposit of grain. As soon as the next box comes uppermost the 85 projection 14 enters one of the notches 19 again and the end 17 of the chute opens to the position shown in full lines, Fig. I, and the grain is deposited into the uppermost box, which is then in position to receive it. As 90 the boxes revolve and the lower one comes uppermost its projection 6 comes against the end 7 of the lever 8 and the rotation of the boxes is stopped.

95 In case the weight 10 should not be sufficient to cause the lever 8 to overcome the momentum of the boxes and stop them when the projection 6 comes against the end 7 of the lever, a device may be employed to insure the stopping of the boxes, and such a device 100 I have shown as consisting of a lever 20, pivoted at 21 to the frame and which has an up-

- wardly and outwardly extending end 22 on the side of the pivot 21 occupied by the upper box, and on the other side of the pivot 21, or the side occupied by the lower box, the lever 5 has an upturned end or projection 23. This latter end of the lever, with its projection, is heavier than the other end of the lever, and, when the boxes are turning, falls upon a projection 25 on the frame 1, as shown in Fig. 10 III; but when the boxes are in their normal position this end of the lever is sustained by the portion 22 of the other end of the lever bearing against a projection 24 on the lower box. As soon as the boxes start to turn the 15 pin 24 leaves this end of the lever, and then the other end of the lever drops onto the pin 25, or into the position shown in Fig. III, allowing the lower box to pass the projection 23. Just as the lower box is reaching its uppermost position a pin 24 on the box which was 20 uppermost comes against the end 22 of the lever and throws the end 23 up into the position shown in dotted lines, Fig. I, thus bringing the end 23 of the lever in the line of the box, 25 permitting the latter end of the lever to strike the box just as the pin 24 leaves the end 22, thus checking the movement of the box, the end 23 of the lever instantly, by reason of its greater weight, dropping back out of the way 30 and elevating the end 22 into engagement with the pin 24 of the box. The distance from the end 23 of the lever to the upturned portion 22 of the other end of the lever is a little greater than the width of the box, so 35 that when the momentum of the box is checked the end 23 of the lever will drop again until the upturned portion 22 of the other end of the lever comes against the pin 24; as shown in full lines, Fig. I.
- 40 Projecting from the web 5 of the boxes is a pin 30, and pivoted to an extension of the frame 1 is a dog 31, having a notched end resting upon pivot 2, as shown. The arrangement of these parts is such that when the 45 boxes have assumed their normal position the pin 30 will have passed under and raised the notched end of the dog 31, so that as the end 23 of the lever 20 engages or strikes the lower one of the boxes the pin 30 will be disengaged 50 from and allow the dog to fall, the pin passing in front of and engaging the notched end

of said dog, thus preventing retrograde or return movement of the boxes.

When the parts are in their normal position, the weighted end of the lever 8 bears 55 against a pin 8^a on the frame 1 and is thus held in its proper position.

I claim as my invention—

1. In a grain-meter, the combination of a suitable frame, a pair of boxes pivoted to the 60 frame with the back of one in line with the back of the other, projections on the boxes at their lower front corner edges, and a counterbalanced lever pivoted to the frame and having an outer inturned end and adapted to 65 be engaged by the projection, substantially as and for the purpose set forth.

2. In a grain-meter, the combination of a frame, a pair of boxes pivoted to the frame, one on each side of the pivot, projections on 70 the boxes at their lower front corner edges, and a counterbalanced lever having an outer inturned end adapted to be engaged by the projections, substantially as set forth.

3. In a grain-meter, the combination of a 75 frame, boxes pivoted to the frame, projections on the boxes, a pivoted counterbalanced lever with which the projections engage, a chute having a hinged end, a cam carried by the boxes, and a pivoted lever engaged by the 80 cam and having a link connection with the hinged end of the chute, substantially as and for the purpose set forth.

4. In a grain-meter, the combination of a frame, a pair of boxes pivoted to the frame and 85 provided with projections, a pivoted counterbalanced lever adapted to be engaged by the projections, and a pivoted lever 20, having ends 22 and 23, one adapted to be engaged by 90 projections on the boxes and the other adapted to engage or strike the boxes, substantially as and for the purpose set forth.

5. In a grain-meter, in combination with a pair of pivoted boxes and a trip for releasing the boxes, a lever 20, having the ends 22 and 95 23, and pins on the boxes for engaging the lever, substantially as and for the purpose set forth.

CHARLES D. SPRAGUE.
